UNITED STATES PATENT OFFICE.

AUSTIN F. JACKSON, OF TAUNTON, MASSACHUSETTS.

DESIGN FOR A SPOON, &c.

SPECIFICATION forming part of Design No. 25,635, dated June 16, 1896.

Application filed April 21, 1896. Serial No. 588,523. Term of patent 14 years.

To all whom it may concern:

Be it known that I, AUSTIN F. JACKSON, a citizen of the United States, residing at Taunton, in the county of Bristol and State of Massachusetts, have invented and produced a new and original Design for the Handles of Spoons and other Similar Articles, such as Forks, Knives, &c., of which the following is a full, clear, and exact specification, reference being had to the accompanying drawings, showing a part thereof.

Figure 1 is a face view of a spoon, showing my design. Fig. 2 is a rear view thereof, and Fig. 3 is a cross-section on about line 3 3 of Figs. 1 and 2.

The leading feature of my design consists in the cross-sectional configuration as shown in Fig. 3, presenting on the obverse side of the handle a central wide corrugation or depression a , flanged on each side by a narrow corrugation or depression a' , extending practically the full length of the widened upper portion of the handle, the central corrugation or depression being continued down the shank B to the lower end thereof.

On the reverse side of the handle, as shown in Fig. 2, I provide scroll-like ornaments C,

from which an edge rib C' extends up to near the end of the handle, where it divides into branches $C^2 C^3$, between which I form by means of beaded scrolls an ornamental figure at C ^{1} .

On the obverse side scroll ornaments D are provided. Opposite the ornaments C on the rear and above such ornaments D, I provide upon the face of handle near its opposite edges rows of bead-like representations D', which extend up to near the upper end of the handle, where they are surmounted by scroll figures D ^{2} , between which is produced the ornament D ^{3} .

What I claim is—

1. In a design for a spoon-handle or similar article the obverse substantially as shown and described.
2. In a design for a spoon-handle or similar article the reverse substantially as shown and described.
3. The design for a spoon-handle or similar article herein shown and described.

AUSTIN F. JACKSON.
